UNITED STATES PATENT OFFICE.

ROBERT LEE WRIGHT, OF LOS ANGELES, CALIFORNIA.

SUPERFIRED CANNON.

Application filed February 20, 1920. Serial No. 360,191.

To all whom it may concern:

Be it known that I, ROBERT LEE WRIGHT, a citizen of the United States, residing at Los Angeles, in the county of Los Angeles 5 and State of California, have invented a new and useful Improvement in Superfired Cannon, of which the following is a specification.

This invention relates to superfired canon, gun and shell combined, a shell within 10 a shell or a plurality of any of same fired at any predetermined time while in flight after being fired from any gun, rifle, cannon, firearm or device capable of firing same and is what might be termed a modified form of 15 my invention as shown by my application #231,849, filed May 1, 1918.

One of the objects of the invention is to provide a gun and shell combined, the exterior part of same being made in a shape to 20 be used as a projectile and a bore therein made in a shape to be used as a gun. It may be made with a smooth bore, or the bore may have rifles as desired, which may be made of any caliber, size, and length, that 25 it may be fired from any gun, rifle, cannon, gun and torpedo combined, fire-arms, or any device capable of firing same, and after being fired as explained, the gun and shell combined may be fired at any predetermined 30 time while in flight or a plurality of same may be loaded within each other and fired one from the other in the same way as above explained, or any projectile or any kind of ammunition may be fired from any of the 35 above mentioned as heretofore explained, in firing one from each other.

One more object of the invention is to provide a shell within a shell with the point of each enclosed or a plurality of same 40 placed within each other in a suitable way to fire each from the other through the point of each point at any predetermined time while in flight after the same has been fired from any gun, rifle, cannon, gun and torpedo combined, firearm or any device capable of firing same. All of the heretofore mentioned may be exploded after being fired while in flight in the same well known way as all projectiles are exploded.

With these and other objects in view the invention consists in the novel details of construction and combinations of parts more fully hereinafter disclosed and particularly pointed out in the claims.

Referring to the accompanying drawings, forming a part of this specification in which

like numerals designate like parts in all the views,

Figure 1 is a longitudinal sectional view of my invention showing my gun and shell 60 combined with the exterior part of same being made in a shape to be used as a projectile and a bore therein made in a shape to be used as a gun.

Figure 2 is the same as Fig. 1 showing the 65 same loaded with a gun and shell combined and projectile in position to be fired at any predetermined time while in flight.

Fig. 3 is the same as Figs. 1 and 2, with 70 a very slight change.

Fig. 4 is the same as Figs. 1, 2 and 3 with very little change, as shown and hereafter explained.

Fig. 5 is a cross sectional view of the modified form of the point of the gun and 75 shell combined as shown in Fig. 6.

Fig. 6 is a longitudinal sectional view of the modified form of the point of the gun and shell combined.

Fig. 7 is the well known timing device and 80 a tube with powder tracing leading from the timer to the explosives to be ignited.

1 is the exterior part of the gun and shell combined showing the same prepared in a shape to be used as a projectile, and 3 shows 85 the bore in the gun and shell combined, showing the same prepared in a shape to be used as a gun the bore of which may be rifled as explained on page 1, line 17. 2 is any suitable kerfed or easily breakable point of the 90 gun and shell combined made in a way and of any suitable metal to break easily upon shock and 4 is the breech block of the gun and shell combined, which closes and locks the breech against movement to the rear 95 during the instant of firing of the gun and shell combined. 5 are the screw threads where the removable breech block 4 is removed from the gun and shell combined, while being loaded from the breech, the 100 same as any other gun, rifle, cannon or fire-arms; and 6 is a removable plug as shown by the screw threads 7, that may be removed in order to remove the timing device 8 from the breech block 5. 7 are the screw threads 105 to remove the plug as stated and 8 is the well known clock-work connected to a shaft 9, in a way to cause the clock work when the spring is wound up like any clock to rotate the shaft 9 in a way to press the lug 110 15 on the shaft back against the lug 13 on the firing pin 12 against the spring 11 in

the casing 10, and as the shaft continues to rotate, the lug 15 on the shaft turns off of the lug 13 on the firing pin allowing the lug 13 on the firing pin 12 to escape through the notch 14 in the shaft 9 at which time the spring 14 drives the firing pin 12 forward and explodes the percussion cap 16. The cap 16 may be recessed in the breech block and made removable with screw threads if desired when using the cap 16 without the cartridge casing, and when the cartridge casing is used the percussion cap is placed in the cartridge casing like all other cartridges are made. The casing 10 around the firing pin may be screwed into the inner part of the breech block and made removable or the breech block and casing may all be made in one piece as desired. The timing device may also be removed 20 from the breech block with screw threads as shown by numeral 18 in Fig. 2. The casing for the cap 16 may also be made attached to the breech block inside the bore of the gun and shell combined as shown. 25 17 is the driving band around the exterior of the gun and shell combined. Any gun and shell combined capable of firing ammunition and any projectile, shell, cartridge, and ammunition desired may be fired from the gun and shell combined or a plurality 30 of same at any predetermined time desired while in flight after the gun and shell combined has been fired from any gun, rifle, cannon, gun and torpedo combined, and firearms or device capable of firing same and after being fired, as heretofore explained, the gun and shell combined or a plurality of same may be exploded as shown by numerals 22, 23 and 24 in Fig. 2; the old 35 style cord fuse as shown by numeral 19 in Figs. 2 and 3, and the well known time fuze as shown in Fig. 7, and any other suitable timing device may be used together or in lieu of the timing device shown by numeral 8, either to fire the gun and shell combined or a plurality of same at any predetermined time and also to explode same after the same have been fired. Any suitable number of guns and shells combined 45 may be loaded within each other and the inner gun and shells combined loaded with a projectile or any suitable ammunition and each fired from the other, at any predetermined time desired while in flight after the 50 same has been fired from any gun, rifle, cannon, gun and torpedo combined, firearms or device capable of firing same, as shown by Figure 2.

Fig. 2 is exactly like Fig. 1 and is operated in every way as Fig. 1, as shown by the numerals having the same meaning in every way as explained in Fig. 1, with the exception that Fig. 2 shows it is loaded with one gun and shell combined and the inner gun and shell combined is loaded with a projectile and other slight changes hereinafter mentioned, and for this reason only the numerals in Fig. 2 that are not shown in Fig. 1 will be explained in explaining Fig. 2. 18 is the screw threads in the breech block 70 where the timing device and percussion cap may be removed from the gun and shell combined when not in use or when desired after removing the timing device by unscrewing the plug 18. Any solid plug may 75 be screwed in if desired to hold the explosive charge 21 in position until it is desired to place the timing device back in position to be used. 19 is the old time well known cord fuze that is ignited when the gun and shell 80 combined is fired from any gun, rifle, cannon, gun and torpedo combined, firearms, or any device capable of firing same, and the predetermined time of firing is adjusted by the length of the cord fuze. As seen by the 85 drawings, when the cord fuse is ignited it burns up near the end 20 and ignites the explosive charge 21 and fires the gun and shell combined and discharges the inner gun and shell combined through the point 2 on 90 the outer gun and shell combined at any predetermined time desired while in flight as heretofore explained. The point 2 on the inner gun and shell combined is made of stronger material or is not kerfed or grooved 95 out so much as the point of the outer gun and shell combined in order that the point 2 on the inner gun and shell combined will break the point 2 on the outer gun and shell combined upon shock without breaking the 100 point 2 on the inner gun and shell combined. Another view of a suitable point for the inner gun and shell combined is shown in Figs. 5 and 6. The time fuze 19 or a plurality of same as shown on the inner gun 105 and shell combined is ignited at the time the inner gun and shell combined is discharged from the outer gun and shell combined and is the old time well known cord fuse and operates in the same well known way as heretofore explained and, as shown, fires the inner gun and shell combined and discharges the projectile from same at any predetermined time desired while in flight after the 110 inner gun and shell combined has been discharged from the outer gun and shell combined. 115 26 is the explosive charge in the projectile and 27 is the screw threads to remove the plug in order to load the projectile with explosives. 28 is the well known cord time fuse as heretofore explained which explodes the projectile at any predetermined time desired while in flight after the projectile has been discharged from the inner gun and shell combined. Any of the timing devices shown in all of the figures and any suitable timing device may be used together or in lieu of the well known cord fuze explained. 120 22 is the explosive charge to explode the gun 125 130

and shell combined at any predetermined time desired after the same has been fired and 23 is the channel with powder tracing leading from the explosive charge 22 to near 5 the end of the gun and shell combined as shown, and 24 is the old time cord fuse recessed in a way that one end of the cord fuse connects with the powder tracing and both the outer gun and shell combined and the 10 inner gun and shell combined are exploded after being fired while in flight as heretofore explained at any predetermined time desired by the cord fuse 24 being operated in the same way as explained in explaining 15 numeral 19. 29 is the screw threads where the point of the gun and shell combined is removed and it is seen that the gun and shell combined may be made with a removable point or the point may not be removable as 20 shown in Fig. 1.

Fig. 3 is the same as Figs. 1 and 2 as shown by the numerals and the numerals shown in both are explained in the same way, the very slight difference being explained hereinafter as follows: 31 is the cartridge casing in which the breech of the gun and shell combined is encased as shown and 32 is the explosive charge in the cartridge casing. 33 is the rim around the end 30 of the cartridge casing and 34 is the well known cap in the cartridge casing. 36 is the projectile in the gun and shell combined in position to be fired from the gun and shell combined at any predetermined time 35 desired while in flight, after the gun and shell combined have been discharged from any gun, rifle, cannon, gun and torpedo combined, firearms or device capable of firing same as heretofore explained in Figs. 1 and 40 2, and 35 is attenuated nose or point made any suitable length to pierce the water at any angle the gun and shell combined is fired in a way that the water may get control of the attenuated nose or point before 45 the large part of the point of the gun and shell combined strikes the water, in order to prevent the gun and shell combined from rebounding when it strikes the water as well as to scatter the water or air as the case may 50 be to all sides and allow the large part of the gun and shell combined to go forward with less air or water pressure resistance. It is obvious that the attenuated nose or point 55 may be made any suitable thickness and length desired to do the work the best and that the gun and shell combined may be made with or without the attenuated nose or point 35 as shown by Figs. 1 and 2.

Fig. 4 is the same as Figs. 1, 2 and 3, as 60 shown by the numerals with the exception of the very slight difference hereinafter explained. 38 is the plug of any suitable soft metal which may be easily broken upon shock recessed in the muzzle of the gun and 65 shell combined as shown by screw threads

37. It may be seen that when this type of a gun and shell combined is fired or discharged from other gun and shell combined, that the end of the muzzle will protect the soft metal recessed in the muzzle of the gun 70 and shell combined in a way that the same will not be broken when fired through the point of other gun and shell combined and at the same time thereafter being fired from a gun and shell combined any ammunition 75 like buck-shot, bullets, shrapnel or any suitable ammunition desired may be fired through the soft metal 38 or the same kerfed in a way to break easily in a way that such as ammunition for shot guns, shrapnel, or 80 any ammunition may be fired through same. Fig. 5 is a cross sectional view of Fig. 6 showing the point of the gun and shell combined to have raised ridges 39, in a way to make such parts of the point of the gun and 85 shell combined strong in order to withstand a shock or lick while the remaining part of the point as shown between the ridges 39 may be made very thin or made of very soft material or metal as is also denoted 90 by numeral 41 in Fig. 6.

Fig. 7 is the well known timing device as shown by 42, and 43 is the dial or scale to set the timing device by to ignite the powder tracing 45 in the tube 44. 44 is any suitable 95 tube or casing to hold a powder tracing and may be made any length to reach the explosive charge desired to be exploded and the tube may be or it may not be perforated as

100 This timing device may be used together or in lieu of any of the other timing devices shown in Figs. 1, 2, 3 and 4.

It is obvious that those skilled in the art 105 may vary the details of the construction as well as the arrangement of parts without departing from the spirit of the invention and therefore, I do not wish to be limited to the above disclosure, except as may be required by the claims.

110 What I claim is:—

1. A combined shell and gun including an outer shell having a bore therein, a kerfed point on one end thereof, a second shell and an explosive charge within said bore, a 115 kerfed point on one end of said second named shell.

2. A combined shell and gun including an outer shell having a bore therein, a kerfed point on one end thereof, a second shell and 120 an explosive charge within said bore, a kerfed point on one end of said second named shell, said second named point being of sufficient strength to pierce said first named point.

3. A combined gun and shell including an outer shell having an elongated bore therein, said bore acting as the bore of a gun, the walls of said bore extending beyond the forward end of a projectile when positioned 130

- therein, a breech block in one end of said combined gun and shell, and time controlled firing means within said breech block, said firing means including a spring pressed firing pin, a rotatable shaft for releasing said firing pin, and clock work means for rotating said shaft.
4. A breech block for a shell comprising a hollow cylindrical externally threaded plug, provided with a time fuse extending therethrough, front and rear apertures in said plug, a closure threaded in each aperture, one of said closures carrying a firing mechanism operative after a predetermined time to fire a detonator associated therewith.
5. A combined gun and shell including an outer shell having an elongated bore therein, said bore acting as the bore of a gun, the walls of said bore extending beyond the forward end of a projectile when positioned therein, a breech block in one end of said combined gun and shell, time controlled firing means within said breech block, said firing means including a spring pressed firing pin, a rotatable shaft for releasing said firing pin, clock-work means for rotating said shaft, and means to fire a plurality of combined guns and shells at a predetermined time after the same has been discharged from any gun, firearms, or device capable of firing same.
6. A gun having its exterior suitably formed so that it may be discharged from the barrel of a gun, said first mentioned gun having a barrel, means to load a plurality of smaller similar guns into said barrel from the breech, means to close the breech of said barrel, and means to discharge said plurality of smaller similar guns from said barrel.
7. A gun having a barrel, the exterior of said gun suitably formed so that it may be discharged from the barrel of a gun, said first mentioned gun having a breech block with a spring pressed firing pin operated with a timing device to explode a percussion cap and fire said gun.
8. A gun having a frangible point formed on the forward end of its barrel, a second gun having a point capable of piercing said point of said first mentioned gun placed within said barrel and a third gun or shell having a point on its forward end adapted to pierce the point of said second gun.
9. A gun having a barrel, said gun adapted to be fired from a gun, the forward end of said barrel of said first mentioned gun being closed, a series of guns concentrically within the barrel of said first mentioned gun and each gun adapted to be fired from each gun enclosing it during the flight and each point capable of piercing the point of the preceding gun.
10. A plurality of guns each having a barrel, the forward end of each barrel being closed, each end being closed having said closure kerfed or grooved, a gun placed with each barrel in way to be discharged from the barrel of each gun through the closed forward end of each gun discharging same.
11. A breech block for a gun having a cavity within provided with a timing device, front and rear apertures in said breech block, a closure threaded in each aperture, said timing device comprising a spring pressed firing pin, a rotating shaft carrying means to engage and disengage means on the firing pin when said shaft is rotated and clock work to rotate said rotating shaft when the spring of the clock work is wound, operative after a predetermined time to explode a percussion cap and ignite the explosive within the breech of the barrel of said gun.
12. A breech block for a gun having a cavity within provided with a time fuze, explosive within the breech of the barrel of said gun, front and rear apertures in said breech block, a closure threaded in each aperture, one of said closures carrying a firing mechanism operative after a predetermined time to fire a detonator associated therewith.
13. A breech block for a gun having a cavity within, a firing device secured within said cavity within said breech block, means to close the rear of said cavity and means to remove said firing means from said cavity within said breech block.

ROBERT LEE WRIGHT.
